UNITED STATES PATENT OFFICE.

GEORGE M. PORTER AND CHARLES YARDUSKY, OF NEW YORK, N. Y., ASSIGNEES OF ONE-
THIRD TO JOHN B. BROOKS, OF NEW YORK, N. Y., AND TWO-THIRDS TO SAID PORTER.

DISPLAY-BOX.

1,334,259.

Specification of Letters Patent. Patented Mar. 16, 1920.

Application filed June 15, 1917, Serial No. 174,977. Renewed September 15, 1919. Serial No. 324,001.

To all whom it may concern:

Be it known that we, GEORGE M. PORTER, a citizen of the United States of America, and CHARLES YARDUSKY, a subject of the Russian Government, and residing at New York, in the county of New York and State of New York, have invented new and useful Improvements in Display-Boxes, of which the following is a specification.

10 This invention relates to display boxes and it has particular reference to a display box which may be formed, by folding, from a properly prepared blank of pasteboard or similar suitable material.

15 One object of the invention is to produce a display box which, when folded, will afford complete protection for its contents, a snugly fitting hinged cover being provided together with a dust guard which will co-operate therewith in two ways, namely, first to frictionally retain the cover in closed position and secondly, to prevent the admission of dust and the like, thereby maintaining the contents of the box in a clean 25 and sanitary condition.

A further object of the invention is to produce a simple and improved construction whereby the hinged cover of the box will be provided with an opening having a 30 transparent cover through which the contents may be displayed and inspected; a hinged flap being provided in addition to said cover for the purpose of overlying the same and protecting the opening having the 35 transparent cover, said flap serving also as a medium on which advertising matter may be conspicuously printed.

40 A further object of the invention is to combine with the box having the hinged cover, a supporting strip which carries the flap overlying said cover, said strip carrying also supporting means whereby the box may be supported in a tilted position, for the 45 purpose of displaying the contents as well as the advertising matter, said supporting means being so constructed and arranged that, when folded for shipment, the said supporting means will occupy an out-of-the-way position beneath the box where it will 50 occupy very little space.

A further object of the invention is to provide an improved construction whereby the supporting strip carrying the hinged advertising flap and the tilting means may 55 be connected with the box without resorting

to the use of paste, cement or other connecting means.

A further object of the invention is to produce a construction whereby the supporting means will be provided with latch members consisting of lugs or extensions that are adapted to be engaged with slits formed in the body of the box thereby enabling the box to be securely assembled for display purposes.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawings,—

Figure 1 is a plan view of a blank from which the improved box may be produced by bending or folding.

Fig. 2 is a plan view showing the blank from which the supporting strip and the flap and tilting means associated therewith are formed.

Fig. 3 is a perspective view showing the box in process of being folded.

Fig. 4 is a perspective view showing the box completely folded and showing also the supporting strip and related parts in process of being applied thereto.

Fig. 5 is a sectional view taken longitudinally through the complete box including the supporting strip and related parts, folded.

Fig. 6 is a transverse sectional view taken on the line 6—6 in Fig. 5.

Fig. 7 is a perspective view showing the box tilted for the purpose of displaying the contents thereof.

Fig. 8 is a plan view of a blank presenting a modified construction.

Fig. 9 is a horizontal sectional view of a box folded from the blank shown in Fig. 8.

Corresponding parts in the several figures are denoted by like characters of reference.

The blank A from which the improved

box is folded contains the material for forming the top, bottom, sides and front and rear ends of the box. Another blank B is provided which contains the material constituting the supporting strip, the attaching means for the same, the hinged top or advertising flap, and the tilting means.

The blank A from which the box proper is formed is scored or creased so as to facilitate the bending thereof on the proper lines and it includes the bottom member 15, front and rear end walls 16, 17 hingedly connected therewith on the lines 18, 19, a dust guard 20 which is hingedly connected with the front wall member 16 on the line 21, a cover 22 which is hingedly connected with the rear wall member 17 on the line 23, side guards 24 hingedly connected with the cover on the lines 25 and side wall members 26 each connected hingedly with the bottom member 15 on a line 27 and each of said side wall members being doubled on the line 28 and provided with a hinged flap 29 which hinges on the line 30. In addition, the blank A is provided with locking wings 31 that are hingedly connected with the front and rear wall members 16 and 17 on the lines 32, said wings being separated from the side guards 24 by slits or incisions 33, and likewise separated from the side wall members 26 and the locking flaps 29 thereof by slits 34. The hinge lines 27 are each provided with a slit 35, the purpose of which will be hereinafter set forth, and the bottom portion 15 is provided with articulate slits 36 forming tongues 37 which may be engaged with the locking flanges 29 for the purpose of securing the latter in position in a manner which is well known and which has long been practised. The cover portion 22 is provided with a cut-out portion forming an opening 38 of any desired size and shape to permit the contents of the box to be inspected, and the contents of the box may be protected by a transparent cover 40 of oil paper or the like which may be pasted or otherwise secured on the cover member 22 beneath the opening 38.

The second blank B from which the supporting strip and related parts are formed comprises a supporting strip 41 which is of a size and shape corresponding with that of the rear wall member 17 of the box in connection with which it is to be used. Hingedly connected with the supporting strip 41 on the line 42 is the top flap 43 which is adapted to overlie the cover 22 of the box so as to form a complete protection for the sight opening 38 and for the transparent cover 40 of said sight opening. Hingedly connected with the lower edge of the supporting strip 41 on the line 44 is a tilting member 45 having laterally extending wings 46 which are hingedly connected therewith on the lines 47 so that said arms

may be folded upon the tilting member, between the latter and the bottom member 15 of the box after the supporting strip and related parts have been assembled with the box as will be presently described. 70

The wings 46 are offset in the direction of each other with respect to the supporting strip 41, the tilting member 45 being of a width slightly less than that of the supporting strip, and the said wings are tapered in 75 the direction of their free ends as shown and each of said wings has a lug or projection 48 constituting a latch member which is adapted to be placed in engagement with one of the slits 35 hereinbefore referred to. 80 If necessary, the wings 46 may be bent or folded on the lines 49 in order to enable said wings to be fitted snugly between the sides of the box when folded. The supporting strip is provided at the ends thereof with 85 attaching flaps 50 hingedly connected therewith on the lines 51.

In folding the blanks A and B to produce the complete display box the front and rear wall members 16, 17 of the blank A are bent 90 upward on the lines 18, 19 and the locking wings 31 associated with said wall members are bent in the direction of each other and overlapped. The side wall members are now bent on the lines 27, 28 so as to include 95 the locking wings between them and the locking flanges 29 are introduced beneath the tongues 37. In this manner the front and rear walls as well as the side walls are secured in perpendicular position with respect 100 to the bottom member 15. The box may now be filled after which the dust guard 20 may be folded down on the contents. The cover 22 is now folded down upon the dust guard and the contents of the box, the side guards 105 24 being introduced between the end edges of the dust guard and the inner faces of the side wall members, being thus held frictionally in a very secure position. The attaching flaps 50 of the supporting strip 41 forming part of the blank B are now introduced between the outermost portions of the side wall members 26 and the proximate faces of the locking flaps 31 until the supporting strip 41 contacts with the rear wall member 115 of the box. The flap 43 may now be folded down on the box cover 22 and the wings 46 may be folded on the tilting member 45 after which the latter is folded flat against the bottom of the box, thus producing in 120 compact form a box which is ready for packing and shipment.

To arrange the box for display purposes the tilting member is folded out from the bottom member of the box and the wings 125 46 are now extended beneath the bottom of the box, the lugs or latch members 48 being introduced through the slits 35. It will be particularly observed that, owing to the fact that the wings 46 are offset in the direction 130

of each other, the top edges of said wings will extend beneath the bottom of the box instead of adjacent to the sides thereof, thus enabling such wings to resist the crushing pressure due to the weight of the box instead of imposing such pressure on the tilting member 45 alone, the box being thus safely retained in a tilted position which is most advantageous for the purpose of displaying 10 the contents thereof.

The tilting member has been shown as being provided with an extension member 55, hingedly connected therewith, and which may be utilized for the purpose of spacing 15 apart the bottom edge portions of the wings 46. This flap however, may be dispensed with when desired.

When the box is tilted for the purpose of displaying the contents the top flap 43 is 20 lifted to the position shown in Fig. 7, thus not only uncovering the sight opening in the cover of the box proper, but also displaying any advertising matter which may have been printed thereon. In connection with this it 25 may be stated that advertising matter of any kind may be printed on the top face of the cover member and also on the external faces of the side walls and the front wall member of the box as well as on the underside of the 30 top flap which will be exposed to view when the box is in displaying position. Particular stress is laid upon the fact that these surfaces, which are the ones exposed to view when the box is in displaying position, may 35 be printed at a single operation, it being understood that the blank B is cut from the same stock as the blank A. This results in a decreased cost of production which is of no little consequence when a large number 40 of articles are to be produced.

Instead of making the blanks A and B separate, as seen in Figs. 1 to 7 inclusive, the said blanks may be combined in a single piece and cut from a single sheet of material. Under this construction, which is 45 clearly shown in Figs. 8 and 9, one of the locking wings 31 is joined with one of the attaching flaps 50, said wing and flap being hingedly connected on the line 60. In setting up the box from this modified blank which in Fig. 8 is designated by C, the wing and flap which are here specially designated by 31', 50' are folded together on the line 60 and are simultaneously introduced 50 between the two thicknesses of material constituting the proximate side wall of the box. In all other respects the construction is as hereinbefore shown and described. It will be evident that any advertising matter may 55 be printed on the surfaces which are principally exposed when the box is arranged for display purposes, by a single operation.

What is claimed, is:—

1. A display box, in combination with a 60 supporting strip externally overlying the

rear wall member, a top flap having hinged connection with the supporting strip and adapted to overlie the cover of the box, and a tilting member having hinged connection with the lower edge of the supporting strip, 70 said tilting member having tapering wings hingedly connected therewith.

2. A display box, in combination with a supporting strip externally overlying the rear wall member, a top flap having hinged 75 connection with the supporting strip and adapted to overlie the cover of the box, a tilting member having hinged connection with the lower edge of the supporting strip, said tilting member having tapering wings 80 hingedly connected therewith, and said wings being provided with latch lugs at their outer extremities; the box being provided with slits in the hinge lines between the bottom member and the side wall members for engagement with said latch lugs. 85

3. A display box having side walls each consisting of two thicknesses of material spaced apart, in combination with a supporting strip of a size and shape corresponding with that of the rear wall of the box, attaching flaps hingedly connected with the sides of the supporting strip and introduced between the two thicknesses constituting the side walls of the box; and a tilting member 90 hingedly connected with the supporting strip. 95

4. A display box having side walls each consisting of two thicknesses of material spaced apart, in combination with a supporting strip of a size and shape corresponding with that of the rear wall of the box, attaching flaps hingedly connected with the sides of the supporting strip and introduced between the two thicknesses constituting the 100 side walls of the box; and a tilting member hingedly connected with the supporting strip, said tilting member having wings hingedly connected therewith and offset in the direction of each other with respect to 105 the supporting strip and adapted to underlie the bottom of the box when extended to support the box in tilted position. 110

5. A display box having side walls each composed of two thicknesses of material, a 115 supporting strip contacting with the rear wall member of the box and having attaching flaps extending between the outer thicknesses of material of the side walls of the box and the locking wings adjacent thereto, a top flap hingedly connected with the top edge of the supporting strip and a tilting member hingedly connected with the bottom edge of the supporting strip. 120

6. A display box having side walls each 125 composed of two thicknesses of material, a supporting strip contacting with the rear wall member of the box and having attaching flaps extending between the outer thicknesses of material of the side walls of the 130

- 4
- box and the locking wings adjacent thereto, a top flap hingedly connected with the top edge of the supporting strip and a tilting member hingedly connected with the bottom edge of the supporting strip, said tilting member having tapered wings hingedly connected with the side edges thereof and adapted to be folded between the tilting member and the bottom of the box.
- 10 7. A display box having side walls each composed of two thicknesses of material, a supporting strip contacting with the rear wall member of the box and having attaching flaps extending between the outer thicknesses of material of the side walls of the box and the locking wings adjacent thereto,
- 15 a top flap hingedly connected with the top edge of the supporting strip and a tilting member hingedly connected with the bottom edge of the supporting strip, said tilting member having tapered wings hingedly connected with the side edges thereof and adapted to be folded between the tilting member and the bottom of the box, said tilting wings being offset in the direction of each other 20 so as to underlie the bottom of the box when extended to support the box in tilted position.
- In testimony whereof we affix our signatures.
- GEORGE M. PORTER.
CHARLES YARDUSKY.
